US0D1045179S

(12) **United States Design Patent** (10) Patent No.: **US D1,045,179 S**
Li et al. (45) Date of Patent: ** Oct. 1, 2024

(54) **NIGHTLIGHT**

(71) Applicant: **Guangzhou EZVALO Technology Co., Ltd.**, Guangzhou (CN)

(72) Inventors: **Yongqi Li**, Guangzhou (CN); **Zhuowen He**, Guangzhou (CN)

(**) Term: **15 Years**

(21) Appl. No.: **35/517,208**

(22) Filed: **May 14, 2022**

(80) **Hague Agreement Data**

Int. Filing Date: **May 14, 2022**

Int. Reg. No.: **DM/221575**

Int. Reg. Date: **May 14, 2022**

Int. Reg. Pub. Date: **May 19, 2023**

(30) **Foreign Application Priority Data**

Dec. 17, 2021 (CN) 202130837626.9

(51) **LOC (14) Cl.** **26-05**

(52) **U.S. Cl.**

USPC **D26/85**

Assistant Examiner — Melissa A Santos

(57) **CLAIM**

The ornamental design for a nightlight, as shown and described.

DESCRIPTION

1. Nightlight
- 1.1 : Front
- 1.2 : Bottom
- 1.3 : Top
- 1.4 : Right
- 1.5 : Back
- 1.6 : Left
- 1.7 : Perspective
- 1.8 : Perspective
- 1.9 : Front view of component 1
- 1.10 : Bottom view of component 1
- 1.11 : Top view of component 1
- 1.12 : Right view of component 1
- 1.13 : Back view of component 1
- 1.14 : Left view of component 1
- 1.15 : Perspective view of component 1
- 1.16 : Back view of component 2
- 1.17 : Bottom view of component 2
- 1.18 : Top of component 2

(Continued)

- 1.19 : Right view of component 2
1.20 : Front view of component 2
1.21 : Left view of component 2
1.22 : Perspective view of component 2
1.23 : Perspective view of component 2
